UNITED STATES PATENT OFFICE

HARRY ALPHONSE WIDMER, OF LONDON, ENGLAND, ASSIGNOR TO TUCK-TITE LOCK & FASTENER COMPANY LIMITED, OF LONDON, ENGLAND, A COMPANY OF GREAT BRITAIN AND IRELAND

FASTENING

Application filed November 10, 1928, Serial No. 318,509, and in Great Britain October 13, 1928.

The present invention relates to improvements in those spring fastenings first described in patent specification No. 1,590,400 June 29, 1926, in which a tab attached to one member of the article to be fastened is fitted with a hinged engaging shoulder controlled by an independent spring and adapted to be pushed under a bridge attached to the other member of the article and to be pressed down against the influence of the spring to allow of the tab being released from the bridge. These spring fastenings have proved very satisfactory in use and have been adapted for widely different purposes. This engaging spring shoulder necessitates a fastening of such a height that it cannot be used conveniently for certain purposes where it is necessary or desirable to reduce the thickness of the article to the smallest dimensions.

The present invention is designed to provide a fastening of this character in which the height is reduced to such dimensions that it can be employed for those purposes where such a spring fastening must lie flush or almost flush with the surface on which it is mounted.

As in the earlier fastening a tab on one member of the article to be fastened is pushed under and engages with a bridge on the other member of the article. The hinged engaging shoulder of the earlier fastening is replaced in the new construction by spring controlled laterally projecting members in the sides of the tab adapted to spring out behind the bridge when said tab has been pushed through. These laterally projecting members are adapted to be easily pressed between the finger and thumb into the interior of the tab to release said tab from the bridge.

It will be readily understood that the height of such a fastening can be reduced to such dimensions that when in use the fastening will lie flush or approximately flush with the surface on which the bridge is mounted and yet provide a strong and efficient fastening entirely satisfactory for the article on which it is employed.

My invention is illustrated by way of example in the accompanying drawings, in which—

Figure 1 shows a perspective view of the fastening according to the present invention. Figure 2 shows a plan view of the tab on an enlarged scale with the top plate of the casing removed.

Figure 3 shows a side view of Figure 2 but with the top plate in position.

Figure 4 shows a plan view on an enlarged scale with the top plate removed, of the tab fitted with a lock.

Figure 5 shows a plan view of the top plate fitted to the fastening shown in Figure 4.

Figure 6 shows a perspective view of an alternative form of bridge, and

Figure 7 shows an enlarged detail of the lock in Fig. 4.

Referring now to Figures 1 to 3 of the drawings a pair of outwardly curving members 1 are pivoted near the end of the tab casing 2 which as usual in this form of fastening is slightly pointed to pass easily under the bridge 3. These outwardly curving members 1 are normally projected intermediate their ends through opposite slots 4 in the side walls of the tab casing 2 under the influence of a leaf or other suitable spring or springs. Such a spring may be conveniently in the form of a U-spring 5 as shown in the drawings, adapted to lie between the said pivoted engaging members 1 the ends of said U-spring being outwardly turned as shown at 6 and adapted to engage in slits 7 cut near the free ends of the pivoted members 1. These pivoted members are provided at their free ends with suitably shaped shoulders 8 adapted to engage with limiting stops 9 on the tab casing which retain the said free ends within the tab casing and also prevent said ends from being pushed too far into the interior of the casing during the operation of releasing the tab from the bridge 3. In use a tab fitted with such a fastening can be easily pushed through the bridge and held in position until the projecting members are pressed between the finger and thumb into the interior of the tab against the influence of their spring to release the tab from the bridge.

It will be noted that the members 1 are pivoted in the forward end of the tab 2 and are under compression when holding the

fastener against release. This enables them to be made from flat stock and to operate in a narrow clearance which is highly desirable in a flat fastener of the type described.

5 Fasteners of this type are used on flexible articles such as leather or fabric bags and the pointed tab entering the bridge prior to the engagement of the fastening members is an essential part of the construction whereby

10 the fastening is readily secured. By pivoting the engaging members in the pointed end of the tab instead of in the opposite end, the length of the tab is thereby condensed making it suitable for flexible articles and less

15 expensive to manufacture.

In Figures 4 and 5 a form of fastening is shown in which the tab casing is fitted with a lock 10 provided with a transverse bolt below the cover 10 which is adapted to be

20 projected by a key to engage the member 1 when in the projected position, and to prevent this member being moved to the released position until the bolt is withdrawn by the key. This lock is shown in Fig. 7 in detail.

25 The bolt 11 slides on pin 20 and has a recess at 21 for the key which raises the bolt against spring 22 engaging the cover 10 and causes tang 23 to clear pin 24 before the bolt is shifted. As shown, the bolt projects on one side

30 only to engage the left member 1. This lock is typical of a variety of locks that may be used for this purpose.

In Figure 6 another alternative form of the fastening is shown in which the horizontal cross bar of the bridge 3 is extended to

35 form a cover plate 12 for the tab when the latter is in engagement with said bridge.

What I claim is:—

1. A flat spring fastening of the character described comprising a bridge mounted on one member of the article to be fastened, a pointed metal tab mounted on the other member of the article to be fastened and adapted to engage said bridge, a pair of opposite outwardly curving engaging members pivoted at one end near the pointed end of the tab casing and having their free ends disposed within said casing and an independent spring adapted to project said opposite outwardly curving engaging members through slots in the side walls of the tab casing.

2. A flat spring fastening of the character described comprising a bridge mounted on one member of the article to be fastened, a

55 pointed metal tab mounted on the other member of the article to be fastened and adapted to engage said bridge, a pair of opposite outwardly curving engaging members pivoted at one end near the pointed end of

60 the tab casing and having their free ends within said casing and an independent U spring between said engaging members adapted to project said opposite outwardly curving engaging members through slots in

65 the side walls of the tab casing.

3. A flat spring fastening of the character described comprising a bridge mounted on one member of the article to be fastened, a pointed metal tab mounted on the other member of the article to be fastened and adapted to engage said bridge, a pair of opposite outwardly curving engaging members pivoted near the pointed end of the tab casing and having their free ends within said casing and an independent U spring between said engaging members with outwardly turned ends adapted to engage in slits cut near the free ends of said engaging members adapted to project said opposite outwardly curving engaging members through slots in the side walls of the tab casing.

4. A flat spring fastening of the character described comprising a bridge mounted on one member of the article to be fastened, a metal tab mounted on the other member of the article to be fastened and adapted to engage said bridge, a pair of opposite engaging members pivotally mounted at one end within said tab and having their free ends provided with shoulders, an independent spring adapted to project said opposite members laterally beyond the side walls of said tab and limiting stops within the tab adapted to engage said shoulders and retain the free ends of said engaging members within the tab and to prevent said engaging members from being pushed to far within the interior of said tab during the operation of releasing the tab from the bridge.

5. A flat spring fastening of the character described comprising a bridge mounted on one member of the article to be fastened, a pointed metal tab mounted on the other member of the article to be fastened and adapted to engage said bridge, a pair of opposite outwardly curving engaging members pivotally mounted at one end within said tab and near the pointed end of the tab casing and having their free ends disposed within said casing, an independent spring adapted to project said opposite members laterally beyond the side walls of said tab and a lock within the tab having a bolt adapted to move between the free ends of the engaging members in the extended position.

In testimony whereof I have signed my name to this specification.

HARRY ALPHONSE WIDMER.
